United States Patent Office

J. M. JOMAIN, OF PARIS, FRANCE.

Letters Patent No. 66,967, dated July 23, 1867.

IMPROVED METALLIC BLIND.

The Schedule referred to in these Letters Patent and making part of the same.

TO WHOM IT MAY CONCERN:

Be it known that I, J. M. Jomain, of Paris, in the Empire of France, have invented certain new and useful Improvements in the Manufacture of Venetian and other Blinds; and I hereby declare the following to be a full, clear, and exact description of the same, reference being had to the accompanying drawings.

The nature of my invention consists in forming a window-blind, door, or other similar article, of sheet iron or other sheet metal, clamped or fluted, as hereinafter described, in order to impart to it the requisite rigidity and stiffness.

It will be readily understood that sheet iron or other sheet metal is entirely too flexible and limber in its ordinary state to be adapted while in such state to the purposes for which I propose to use it. In order to make it unyielding and stiff I take a piece of sheet iron, for instance, of the size required for the door or blind, as the case may be, and by means of blocks or clamps, and mechanism for actuating the same, or by the employment of other suitable mechanism for stamping or moulding, or clamping the metal, I form around or near its edge a fluting or moulding, having either a concavo-convex or other suitable form. This moulding takes away from the sheet all its limberness and stiffens it to such a degree that it will retain its shape under any pressure which a door or window-blind is required to withstand. I am thus enabled to make the blind or door of a single sheet of metal, which not only possesses extreme rigidity, but is very cheap and durable; and while it takes up much less room than the ordinary blind or door, affords much more complete protection than they against danger from fire or thieves, &c.

My invention for the reasons above given may be applied with special advantage to the manufacture of Venetian blinds, which can be struck up and moulded rapidly and with comparatively little labor.

In order to form in the blind "slats" resembling those of an ordinary window-blind, I make in the metal sheet a series of incisions parallel with and equidistant from each other. A portion of the sheet is thus divided up into a series of strips to which the appearance of "slats" may be given by twisting or turning each strip by suitable means until it has the inclined position which ordinary "slats" occupy.

To enable others skilled in the art to understand and use my invention, I will now proceed to describe the manner in which the same is or may be carried into effect, by reference to the accompanying drawings, in which—

Figure 1 represents an elevation of a Venetian blind composed of three sections or leaves.

Figure 2 is a horizontal section on the line Y Y.

Figure 3 is a vertical section on the line X X.

Figure 4 is a top view of the blind, showing the sections folded back into a suitable recess formed in the window-frame.

Figures 5 and 6 are modifications of my invention.

The blind, shown in fig. 1, is composed of three leaves A A' A'' made of sheet iron about two millemetres in thickness. Each leaf has formed in it and near its edge a continuous concavo-convex moulding or fluting, a a' a'', by which, as above explained, the iron is stiffened. The contour of this moulding or fluting is shown in fig. 3. It will, of course, be understood that the form there represented need not be strictly adhered to, as the fluting may have a more or less ornamental and irregular form, as desired. The three leaves are connected by hinges, C C', while the leaf A'' nearest the window P is hinged thereto at C''. They are capable of being folded back against the frame P, or in a recess formed in the frame so as to occupy but little room, as shown in fig. 4. They may be held in this position by means of claws b b, which engage with suitable catches in the window-frame P. In order to form the slats of the blind, a series of incisions is made in the same, parallel with and equidistant from each other. These incisions may be either straight, as shown at D, fig. 1, or curved, as indicated at D', or they may be of any shape desired. The blind, or rather a portion of it, is thus divided up into a series of strips, which, by being bent so as to occupy an inclined position, as above explained, resemble in all essential respects the ordinary "slats" of wooden blinds. The position occupied by the strips when thus bent is shown plainly in figs. 2 and 3, where the plane in which each slat or strip D'' lies is at angles to the vertical plane of the blind. The blind when the leaves are extended, as shown in fig. 1, may be locked or held in position by means of bolts m, or other suitable fastening devices.

Figures 5 and 6 represent my invention as applied to a door; the door in fig. 5 being formed with blinds while that shown in fig. 6 has none.

Figures 7 and 8 are sections of the doors, shown respectively in figs. 5 and 6. In a case like the present, where the form of the piece is such as to admit of two sets of mouldings, they may be formed as shown in the figures, the convexity of the moulding surrounding the part Q being upon one side of the door, and the convexity of the moulding surrounding the part above being on the opposite side. The door is thus strengthened and made capable of resisting strain coming from either side. In case, however, that the convexity of the fluting is all upon or towards one side of the door or blind, as seen in fig. 1, then this side of the blind or door should be turned towards the exterior of the building, for the reason that it would resist better the efforts of any one attempting to break or injure the shutter or door than the other or "concave" side.

It will be seen that my invention is capable of being varied in many particulars, so that the blinds or other articles to which it is applied can be made highly ornamental; and, as above said, besides being more durable and cheaper than ordinary blinds, the blinds constructed in accordance with my invention afford better protection, and may be folded away so as to take up much less room than they.

Having now described my invention, and the manner in which the same is or may be carried into effect, what I claim, and desire to secure by Letters Patent, is—

1. A window-blind or door constructed of a metallic plate fluted around and on its sides, and provided with slats formed in the said plate, as and for the purposes shown and described.
2. A window-blind or door, of sheet iron or other sheet metal, in which the slats are formed from strips partially detached from the said metal sheet and bent substantially as herein described.

J. M. JOMAIN.
